UNITED STATES PATENT OFFICE

PHILIP L. HOWE, OF WILSON, TEXAS

AUTOMOBILE RADIATOR CONDENSER

Application filed December 9, 1931. Serial No. 579,868.

My invention relates to improvements in automobile radiator condensers.

The object of my invention is to provide a novel condenser, adapted to be attached to the discharge end of a radiator overflow pipe, which is simple, cheap, durable, not likely to get out of order, which may be readily and quickly mounted upon or removed from an automobile, as a unit, without alteration of the structure of the automobile, and with which air and carbonic acid gas may be automatically removed from the water or alcoholic mixture in the radiator, whereby the cooling liquid in the radiator may have its boiling point raised to a considerable extent over that of the liquid containing air and carbon dioxide gas, thus, with the elimination of these elements very much lessening the corrosion of the metal of the radiator and rusting of the interior of the water jacket.

The invention provides further novel means permitting the discharge from the condenser of the air and carbon dioxide gas and vapor while preventing the intake therein from the atmosphere of air or gases.

The novel features of my invention are hereinafter fully described and claimed.

In the accompanying drawing which illustrates my invention, Fig. 1 is a reduced side elevation of my improved condenser shown mounted on an automobile and connected to the overflow pipe of the radiator.

Fig. 2 is an enlarged front elevation of one form of my invention which employs a collapsible soft rubber tube as a valve for closing the outlet and as a duct for conveying air and gas from the outlet to the atmosphere.

Fig. 3 is an enlarged section on the line 3—3 of Fig. 2.

Fig. 4 is an enlarged section on the line 4—4 of Fig. 2, showing the eduction tube collapsed and closing the outlet.

Fig. 5 is a view similar to Fig. 4, showing the eduction tube expanded so as to serve as an open duct.

Fig. 6 is a reduced top view of the container shown in Fig. 2.

Fig. 7 is a side elevation, showing a modified form of the valve.

Fig. 8 is a section on the line 8—8 of Fig. 7, the flexible valve strip being shown on the closed position.

Fig. 9 is a view similar to Fig. 8, showing the flexible strip expanded so as to form with the body of the container an open duct leading from the outlet to the atmosphere.

Similar characters of reference designate similar parts in the different views.

Referring to Figs. 1 to 6, 1 designates the body of a liquid container comprising, preferably, an expandable bag of soft rubber, non-porous flexible fabric or other suitable material, the container being normally closed to the atmosphere and adapted to hold liquid.

The lower end of the body 1 has an inlet comprising a flexible tube 2 of soft rubber or other suitable material which is adapted for attachment to the discharge end of a radiator overflow pipe 3 of usual type, the upper end of which terminates in the radiator 4 directly under the radiator cap 5, Fig. 1.

The body 1 at one side thereof above the inlet tube 4 and near the top of the body has an outlet 6 over which is disposed a collapsible tube 7, preferably of thin soft rubber, one side of said tube 7 being made integral, as by cementing, with the body 1. Said side of the tube 7 has an opening 8 therethrough which registers with the outlet 6.

For suspending the body 1 it is provided at its upper end with a tab 9 having a hole 10 therethrough adapted to receive any supporting device, as a pin 11 on the dashboard.

The other side of the tube 7 forms a valve comprising a flexible strip normally held by atmospheric pressure against the opposite side so as to normally close the opening 8 and the outlet 6. Upon a pressure in the container greater than atmospheric, such pressure expands the tube 6, as shown in Fig. 5, so as to form an open duct leading from the opening 8 and outlet 6 to the atmosphere, thus permitting air, vapor and dioxide gas to escape from the container to the atmosphere. Upon the internal pressure decreasing, the side of the tube 7 distant from the body 1 will collapse and again close the opening 8 and outlet 6, thereby preventing air or gas

entering the container through the outlet 6 and tube 7.

In the operation of the device just described, the cap 5 of the radiator 4 is removed and the radiator is filled with the cooling liquid. The engine is then run so as to heat the liquid and cause it to expand and part of it with the air and gas will pass from the overflow pipe 3 through the tube 2 into the body 1, creating a pressure in the latter sufficient to expand the tube 7 and thereby permit air and dioxide gas to escape through the tube 7 to the atmosphere.

Upon repeating this operation several times, the most of the air and carbonic dioxide gas will be eliminated and discharged to the atmosphere automatically.

Upon cooling of the radiator, the liquid in the body 1 will be forced by atmospheric pressure on the outside of the body 1 back into the radiator.

As is well known, water or mixed water and alcohol, when so treated as to have the air and dioxide gas discharged therefrom, can be raised to a point considerably above its previous boiling point without boiling, thereby enabling the engine to be run at a higher temperature without boiling the cooling liquid.

30. In the form of my invention shown in Figs. 7, 8 and 9, 12 designates a flexible expandible strip, composed of soft rubber or other suitable material integrally fastened, as by cementing, at one or more of its edge portions, as indicated in dotted lines in Fig. 7, and having a free portion 13 which forms a valve covering and normally closing the outlet 6 of the expandible container body 1 to which the strip is attached.

40. When the pressure in the body 1 rises above atmospheric the expandible free portion 13 of the strip 12 will be expanded, as shown in Fig. 9, thus forming a duct 14 connecting the outlet 6 with the atmosphere, whereby air, vapor or gas can escape from the container to the atmosphere. As soon as the pressure lowers in the radiator 4 and the container body 1, the portion 13 will retract to the closed position, shown in Fig. 8.

50. To disconnect the condenser, as exemplified in either of the forms shown in the drawing, it is but necessary to lift the body 1 off from the pin 11, and withdraw the inlet tube 2 from the overflow pipe 3. By reversing this simple operation the condenser may be replaced in operative position.

60. By closing the radiator 4 to the atmosphere by applying thereto the radiator cap 5, and attaching the inlet tube 2 to the overflow pipe 3, the radiator 4 is sealed against loss of water or alcohol unless the cooling liquid in the radiator is heated to its boiling point, and by reason of the use of my improved sealing condenser, which automatically effects the eliminating from the cooling

liquid of most of the air and carbon dioxide gas, the boiling point of the cooling liquid is raised to a very considerable extent above that which it had when placed in the radiator, thereby enabling the running of the engine at a higher temperature without boiling of the cooling liquid than could be done without the employment of the sealing condenser.

70. By having the flexible strip comprising the valve held normally closed and the container normally held collapsed solely by atmospheric pressure, as shown and described, the valve will be opened by any internal pressure greater than the external atmospheric pressure, whereby the air and dioxide gas can be eliminated and discharged to the atmosphere, as has been described, with a minimum of running of the engine.

75. I do not limit my invention to the structures shown and described, as other modifications, within the scope of the appended claim, may be made without departing from the spirit of my invention.

80. What I claim is:—

85. In an automobile radiator condenser, an expandible flexible closed container for liquid normally held collapsed solely by external atmosphere pressure and having an inlet 90 adapted for connection with the discharge end of a radiator overflow pipe, and having above said inlet an outlet, said container having a flexible strip integral therewith and having a free portion normally held solely by atmospheric pressure against said container and closing said outlet, said portion being movable by any pressure in said container greater than atmospheric to uncover said outlet.

95. In testimony whereof I affix my signature. 100
PHILIP L. HOWE.
